UNITED STATES PATENT OFFICE.

JAMES M. TAFT, OF SOUTH HEART, NORTH DAKOTA.

HAND-CAR.

SPECIFICATION forming part of Letters Patent No. 495,529, dated April 18, 1893.

Application filed July 16, 1892. Serial No. 440,236. (No model.)

To all whom it may concern:

Be it known that I, JAMES M. TAFT, a citizen of the United States, residing at South Heart, in the county of Stark and State of North Dakota, have invented certain new and useful Improvements in Hand-Cars; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to an improvement in that class of hand cars used more particularly for one or two passengers although it may be used in other ways.

20 My object is to provide means for effecting greater speed and to construct the arrangement so that it will be light and durable.

To this end my invention consists of certain novel features and combinations of parts more fully described hereinafter and pointed 25 out in the claims.

Referring to the accompanying drawings which illustrate my invention: Figure 1 represents a longitudinal section of my invention; Fig. 2, an end elevation; Fig. 3, a detail 30 view of the tension device for keeping the sprocket chain employed taut; Fig. 4, a detached view of the operating lever. Fig. 5 is a perspective view of the pin for holding the lever in place.

35 The reference letter *a* represents the framework of my improved machine, having the lateral extending cross-pieces *b*, and arched portion *c*. The cross-pieces *b* have formed integral therewith, bearing boxes *d*, in which 40 the axles *e* and *e'* are journaled. The arched portion *c* of the frame *a*, is formed preferably of metal and is arched to secure greater strength and rigidness. Extending longitudinally with the portion *c*, directly under 45 the top of its arch, is a brace or girder *f*, which serves the double purpose of strengthening the arch and holding in place the lever-socket *g*. This socket is secured to the under side of the arch *c*, and has formed in it 50 on each side a series of holes *h*. These holes

are formed with a large circular portion *h'* said circular portion having an extension or arm *h*² projecting downwardly from it.

The operating lever *i* is adapted to fit into and extend through the socket *g*, and is fulcrumed therein by means of the pins *j* which project through the openings *k* formed in the lever and the openings *h* in the socket. Each of these holes *k* and *h* are the same in number and shape and register with each other. The pin *j* has formed on one end, integral therewith, an extension *j'* which registers with the arm *h*² of openings *h* and *k*. This extension is after the pin has been inserted in place thrown around opposite the arm *h*² by means of the weighted arm *j*² which movement securely locks the pin in place. The holes *k* and *h* are located in vertical lines in their respective places and by changing the pin *j* from one to another the 65 leverage of the lever *i* may be changed to suit the exigencies of the occasion. It will also be noticed that by arranging a series of holes in both socket and lever that the distance which the latter is raised or lowered 70 may be regulated with greater facility.

Rigidly fixed to each of the axles *e* and *e'* is a stationary ratchet, clutch member *l*, which is adapted to operate in conjunction with the loose member *m*. To this member *m*, is rigidly secured a sprocket wheel *n*, and the loose member is held in engagement with the member *l* by means of a coil spring *o* bearing against a rigid collar *p*, all of which are secured to the axles, as shown in the drawings. 80 Working over the sprocket wheels *n* *n*, is a sprocket chain *q* which has its ends adjustably secured to the lower end of the operating lever *i*, by means of the arrangement illustrated by Fig. 3. This attachment is used 85 for taking up the slack in the sprocket chain *q*, or for keeping it the desired tension, and consists of a clevis *r*, secured to the lower end of lever *i* by means of a pin *r'*. The shank or bolt *r*² of the clevis is threaded and operates with an internally threaded hook *r*³, to which one end of the sprocket chain is secured. By turning the hook *r*³ it follows that the hook will be advanced toward the lever 90 or moved away from it, which will increase 95 100

or decrease the tension of the sprocket chain. The remaining end of the chain *q* is securely fastened to the other side of the lever *i*.

An idler sprocket wheel *s* is journaled in one end of the frame *a*, over which idler the chain *q* is passed. By changing the chain so that it will pass above or below the sprocket wheel nearest to the idler *s*, the direction in which said wheel is rotated may be changed, thus allowing both axles to be worked in unison or alternately.

Adjustably secured to the arch *c* by means of the link *t* are the seats *u*. The links *t* are secured in place by means of pins *t*³ and a series of holes *t'*. By this means the seats may be moved to or from the lever *i*, to suit the convenience of the operator. Depending from the under side of these seats are braces or props *u'* which have their free ends seated in the notches formed in the blocks *v*. This arrangement allows the incline of the seats to be adjusted also. The lever is operated by means of the foot rests or spurs *w* at its lower end and cross pieces *x* at its top, the latter serving as handles to be grasped by the operator.

In using my improvement, the operator or operators are seated opposite each other on the seats *u*, and by means of the foot rests *w*, and the handles *x*, the lever *i* is made to oscillate, which will through the medium of the sprocket chain *q*, impart an intermediate rotary motion to the loose clutch members, thereby rotating the axles and their wheels.

Having thus described my invention, what I claim as new, and desire to secure by Letters Patent, is—

1. In a hand car, the combination of a rocking lever, a sprocket chain attached thereto, and clutches secured to the car axles and operated by the sprocket chain, substantially as described.

2. In a hand car, the combination of a rocking lever, an adjustable fulcrum therefor, a sprocket chain attached to the lever and clutches secured to the car axles and operated by the sprocket chain, substantially as described.

3. In a hand car, the combination of a rocking lever, a sprocket chain attached thereto and ratchet clutches secured to the car axles and operated by the sprocket chain, substantially as described.

4. In a hand car, the combination of a frame, an arch fixed thereto, a lever having its fulcrum in the arch, a sprocket chain and clutches, substantially as described. 55

5. In a hand car, the combination of a frame, an arch secured thereto, one or more seats secured to the arch, a lever fulcrummed on the arch, a sprocket chain and clutches, substantially as described. 60

6. In a hand car, the combination of a lever, a sprocket chain attached thereto, a tension device on the sprocket chain and one or more clutches operated by said sprocket chain, substantially as described. 65

7. In a hand car, the combination of a lever, a clevis secured to the lower end of said lever, a threaded shank on the clevis, a hook working on the threaded shank, a sprocket chain one end attached to the hook and one or more clutches operated by the chain, substantially as described. 70

8. In a hand car, the combination of a frame, one or more seats pivoted thereto, a brace under each seat, and blocks located at a point below the seats and having an inclined series of notches formed in them by which the free ends of the braces are held in place, substantially as described. 75

9. In a hand car, the combination of a lever, a sprocket chain attached thereto, clutches operated by the sprocket chain and an idler sprocket wheel operating in conjunction with one of the clutches, substantially as described. 80

10. In a hand car, the combination of a lever, a sprocket chain, a rigid ratchet clutch member fixed to the car axle, a loose member located on the axle adjacent to the fixed one over which member the sprocket chain works and a spring and collar for holding the two clutch members in engagement, substantially as described. 90

11. In a hand car, the combination of a rocking lever, a sprocket chain having its ends attached thereto, and clutches operated by the sprocket chain which is adapted to reciprocate over them, substantially as described. 95

In testimony whereof I affix my signature in presence of two witnesses.

JAMES M. TAFT.
